[57] CLAIM

The ornamental design for a golf club head, as shown and described.

DESCRIPTION

FIG. 1 is a perspective view of the present golf club head;
FIG. 2 is a front elevational view of the golf club head, looking at the face of the head;

FIG. 3 is a rear elevational view of the golf club head;

FIG. 4 is a view generally from the top of the golf club head looking parallel to the club face;

FIG. 5 is a bottom view of the golf club head;

FIG. 6 is a toe view of the golf club head;

FIG. 7 is a heel view of the golf club head, looking at the hosel of the head;

FIG. 8 is a perspective view of a second embodiment of the golf club head as disclosed in FIG. 1;

FIG. 9 is a front elevational view of the golf club head shown in FIG. 8, looking at the face of the head;

FIG. 10 is a rear elevational view of the golf club head shown in FIG. 8;

FIG. 11 is a view generally from the top of the golf club head shown in FIG. 8 looking parallel to the club face;

FIG. 12 is a bottom view of the golf club head shown in FIG. 8;

FIG. 13 is a toe view of the golf club head shown in FIG. 8; and,

FIG. 14 is a heel view of the golf club head shown in FIG. 8.

CERTIFICATE OF CORRECTION

PATENT NO. : Des. 426,604
DATED : June 13, 2000
INVENTOR(S) : Philippe Besnard et al.

Page 1 of 3

It is certified that error appears in the above-identified patent and that said Letters Patent is hereby corrected as shown below:

Title page.

The title page, showing the illustrative figure, should be deleted and substitute therefor the attached title page.

Drawings.

The drawing sheet consisting of Fig.8, should be deleted to be replaced with the drawing sheet consisting of Fig. 8, as shown on the attached page.
